UNITED STATES PATENT OFFICE

105,998

DESIGN FOR A COMBINED MOTOR INCLOSURE AND SUPPORT FOR TRACTORS

John R. Morgan, Oak Park, Ill., assignor to Sears, Roebuck and Co., Chicago, Ill., a corporation of New York

Application October 24, 1936, Serial No. 65,478

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Combined Motor Inclosure and Support for Tractor, of which the following is a specification, reference being had to the accompanying drawing, forming a part thereof.

Fig. 1 is a top plan view of a combined motor inclosure and support for tractor;

Fig. 2 is a side elevation of the same; and
Fig. 3 is a front elevation of the same.
The side of the hood opposite to that shown in Fig. 2 is similar to the side shown.

I claim:

The ornamental design for a combined motor inclosure and support for tractor, as shown and described.

JOHN R. MORGAN.
